UNITED STATES PATENT OFFICE.

HENRY L. DOHERTY, OF NEW YORK, N. Y.

METHOD OF CONDUCTING COMBUSTION.

1,187,051.

Specification of Letters Patent. Patented June 13, 1916.

Application filed November 15, 1911. Serial No. 660,453.

To all whom it may concern:

Be it known that I, HENRY L. DOHERTY, a citizen of the United States, and a resident of New York city, in the county of 5 New York and State of New York, have invented certain new and useful Improvements in Methods of Conducting Combustion, of which the following is a specification.

10 This invention relates to a method of conducting combustion.

The object of my invention is to furnish a method of conducting combustion, applicable either to furnaces or gas producers, 15 whereby I am able to secure absolutely automatic stoking and to maintain the fuel bed free from clinker and in such an open condition as will permit the free and unobstructed passage of the draft current.

20 Briefly stated, my invention consists in feeding the fuel into the furnace through a comparatively high vertical or inclined (preferably vertical) feed chute, through and past a combustion zone wherein such

25 fuel undergoes combustion, withdrawing the material from the combustion zone at a rate faster than the rate of combustion therein, cooling the said material by a current of cool gas which is advantageously 30 cured by withdrawing through the feeding chute in contact with the cold fuel a portion of the gases from the combustion zone or region to heat said fuel and cool said gases, introducing the said cooled gases into the

35 cooler part of the furnace beyond said zone and passing them up in contact with the hot mixture of fuel and ash withdrawn from the combustion region to cool said mixture and heat said gases, returning said gases to

40 said zone, screening the cooled material withdrawn from the cooler part of the furnace, returning the over-screen portion of the said material to the top of the feed chute of the furnace, and feeding it back 45 to the furnace together with fresh fuel.

It is to be noted that the combustion of the fuel in the combustion zone proper may be carried out with the production of either 50 gases of complete combustion or the production of combustible gases similar to ordinary producer gas. This latter specific modification of the broad invention, herein claimed, I disclose and claim in my application Ser. No. 660449, filed of even date 55 with this application. The claims of this

present application are directed to the broad invention and to the specific case of carrying out the combustion to produce gases of complete combustion.

In the accompanying drawings I have 60 shown a form of apparatus suitable for carrying out my invention.

Figure 1 is a vertical section through the furnace, showing also the blower, screening device and elevators. Fig. 2 is a part section on the same plane showing the grate 65 revolved into such a position that the fuel is free to assume its natural angle of repose in chamber 1 on both sides of the same.

1 is the combustion chamber of the 70 furnace, 2 the feed chute, 3 the cooler or ash pit, 4 the grate, 5 a fuel discharging device, 6 a grizzly or other screening device for 75 separating the fines from the material discharged.

7 is a hopper for the return of the over-screen portion of the material withdrawn at the bottom of the furnace.

8 is a feed hopper for fresh coal.

9 is either a steam jet or mechanical 80 blower for creating a forced draft in the furnace.

10 is the inlet space below the grate 4 for the introduction of primary current when the latter is set for direct firing.

11 is the space above the fuel bed formed 85 between the surface of the fuel and the walls of the chamber.

12 is the gas flue which conducts the hot 90 combustion gases from the furnace to the flues of a boiler or other apparatus in which they are utilized for heating.

13 is an elevator for raising the over-screen portion of the material withdrawn at the bottom of the furnace to the hopper 7.

14 is a coal conveyer which supplies the 95 fresh fuel to the hopper 8.

15 is the gas off-take at the top of feed chute 2.

16 is a mechanical or jet blower which 100 draws off a portion of the furnace gases through 15 and forces them through the pipe 17 into the lower part of the fuel cooler 3.

18 is the space left between the end of the 105 grate 4 (when the latter is in use) and the wall of the furnace chamber 1.

By varying the position of grate 4 from the position shown in Fig. 1 to that shown in Fig. 2, which latter is above the angle of repose of the fuel, any thickness of fuel may 110

- be maintained between the primary current inlet space 10 and the gas off-take space 11 up to the limitations of the apparatus. In this position of the grate the apparatus may 5 be operated the same as an ordinary gas producer, except for the fact that the direction of flow of the draft current will be laterally across the fuel bed instead of in a vertical direction through the same.
- 10 Assuming that the grate is set in the position shown in Fig. 1, the method of operating the apparatus to carry out my invention would be as follows: Either fuel or coarse cinder is charged into the top of the fuel 15 chute 2 and permitted to fall over the grate and into the cooler 3 occupying the lower part of the furnace. This material is charged until the mass in the cooler 3 is built up to the space 18 left between the end 20 of the grate and the wall of the furnace. Kindling is now charged onto the grate 4 through 2, and ignited. More coal is now introduced through 2 until a bed of ignited coal has been built up on the grate 4. As 25 this latter is set either on or slightly below the angle of repose of the material, the coal as it is charged tends to build up against the wall of the furnace at the space 18 and then on its natural angle of repose over the face 30 of the grate until it has filled up to the bottom of the chute 2. The coal may now be rapidly charged into the chute 2 until the latter is full. The air for supporting combustion enters the furnace through the 35 damped air inlet 19, passes into the space 10 below the grate, thence through the interstices of the grate into the ignited fuel thereon, the oxygen of the air uniting with a portion of the carbon of the fuel, the resulting gases discharging from the fuel bed 40 into the gas space 11 above the same. From 11 the combustion gases pass through the flue 12 into the boiler or other heating apparatus in which it is intended to be used.
- 45 By means of the steam blower 9 the furnace may be operated under forced draft the same as an ordinary boiler furnace. Instead of 9, a mechanical blower of any type desired may be used. The apparatus is now 50 in shape to be put in normal operating condition. Either continuously or intermittently part of the mass occupying chamber 3 is withdrawn through the discharging apparatus 5. The material discharged through 55 5 falls onto a grizzly or other screening device, 6. Passing over screen 6 the fine ash of the mixture of fuel and ash discharged from 3 falls through the interstices between the bars or through the apertures of the 60 screen, while the coarser material discharges over the lower end of the screen into the boot of the elevator 13. It is then raised by 13 to the top of the furnace and discharged into the hopper 7, which discharges into the feed 65 chute 2. As material is withdrawn from the
- bottom the proper proportion of fresh coal which is required to be mixed with the coked fuel to maintain the supply to the combustion chamber 1 at the normal point is introduced through the hopper 8. The coal is fed 70 continuously into 8, or intermittently as may be desired, by means of the coal conveyer 14, or any other preferred type of conveyer. The conveyer shown comprises a traveling chain of linked buckets which runs over the 75 fuel hopper 8 and under the ash hopper 21. The conveyer is advantageously of the tip-bucket type in which the buckets can be discharged at any desired place on their path of travel by setting a tripping device provided for that purpose. As material is withdrawn at the bottom, the fuel mixture falls by gravity from the chute 2 onto the grate 4. In passing over 4 more or less of the fuel is burned, according to the rate at 80 which the fuel mass is withdrawn through 5 and the velocity and volume of the draft.
- In regulating the rate of withdrawal of the fuel from 3, and consequently the rate of feed of the fuel onto the grate or into 90 the combustion chamber 1, when the grate is not used, two considerations must be borne in mind. In the first place, it is necessary to draw the material from the bottom of the furnace at a rate such that sufficient 95 coked fuel will be available to secure the proper proportioning of the fuel mixture fed to the furnace, with regard to the caking character of the fresh fuel. If this latter possesses marked caking qualities a 100 larger proportion of coked fuel is required in the mixture to prevent the formation of pasty aggregates by the fragments of the fresh coal than is necessary with hard fuel or a fuel intermediate between the two. 105 Nearly all coals, even the impurer grades of anthracite, will soften more or less when first exposed to high temperatures. In the case of true coking coals, there is apparently an actual semi-fusion of the coal itself, the 110 pasty lumps uniting at their surfaces of contact to form coke aggregates in the well known manner. In the case of ordinary soft coals, no true coke is formed, but, when the fuel is first heated, it becomes more or less 115 softened and, in the presence of a considerable proportion of ash, becomes entangled with the pasty ash particles in the clinker. In the case of the smaller sizes of anthracite, which nearly always contain a large 120 proportion of mineral, or ash-forming matter, of comparatively easy fusibility, it is seldom that the material rejected from the grate contains less than 50% of combustible matter. This is due to the formation of 125 clinkers by the ash and a portion of the unburned fuel. The masses of coke or clinker thus formed act to impede and, in some cases, to practically shut off the draft through the fuel bed. This action I largely 130

prevent by my invention, by mixing with the raw fuel a suitable proportion of pre-formed coke. Coke requires a temperature much above that of its formation to cause it 5 to again soften. By using a suitable proportion of coke in the fuel mixture therefore, I, to a large extent, separate the coal particles from each other so that when they are softened by heat they are prevented 10 from coming into contact and so forming aggregates. In the second place, sufficient unburned fuel should be maintained on the grate 4, or in the chamber 1, to keep the ash residue from the portion of the fuel 15 burned down to a comparatively small proportion of the mixture. Even, therefore, when sufficient coked fuel can be obtained by a moderate rate of drawing to satisfy the first requirement, it is sometimes necessary 20 to increase the rate in order to provide the necessary coked fuel to satisfy this second requirement. By thus keeping the proportion of free ash in the fuel bed in the combustion region comparatively low I am 25 able to prevent the formation of clinkers, since the large proportion of unburned and coked fuel in the mass prevents the union of the pasty ash particles to form clinkers. In the same manner the coke in the fuel bed 30 serves to separate and prevent the agglomeration of the coal fragments which have been softened and rendered pasty by the heat. With easily fusible ash it is advantageous to so regulate the speed of advance 35 of the fuel column that the proportion of free ash in the mixture of ash and unburned fuel in 3 will not exceed 5% of the total weight of the mixture. With other fuels whose ash is more infusible the rate of advance of the 40 fuel may be regulated to that which will produce a mixture having as much as 20% of free ash in 3 without causing any serious retardation of the draft. Usually, however, the fuel column should be advanced at 45 a rate that will prevent an increase in the proportion of free ash in the mixture in the cooler 3 above 10% of the mixture. It is obvious that by using a sufficiently rapid rate of advance of the fuel column and a 50 sufficient proportion of coarse coke or carbonized fuel in the initial fuel mixture, I can maintain the fuel column in a condition that will maintain a good proportion of "voids" in the mass, thus insuring the 55 maintenance of a comparatively free and unobstructed passage for the draft current. By thus always maintaining a comparatively large proportion of unburned and coked fuel on the grate 4 or in the chamber 1 and in the chamber 3, I am able to maintain the fuel bed in an open condition affording free passage to the draft current passing through it.

During normal operation, by means of the 65 blower 16 (which is preferably of a mechani-

cal type, although a steam jet similar to that shown at 9 may be substituted for the mechanical device) a portion of the gases produced in furnace chamber 1 is drawn up through feed chute 2 in contact with the 70 fresh fuel filling the same, down through the pipe 15, and forced through pipe 17 into the bottom of the cooler 3. Owing to its being brought into contact with the cold fuel in passing through chute 2 the initially hot 75 gases from chamber 1 are cooled down to a temperature below that of ignition of the fuel. At the same time, the fuel in the lower part of chute 2 is heated up to the temperature of carbonization and most of the volatile constituents of the fuel are distilled 80 therefrom. When the furnace is working with a thin fuel bed the gases passing up through 2 will contain more or less carbon dioxid which will be to some extent reduced 85 to carbon monoxid as the gases pass in contact with the incandescent carbonized fuel in the lower part of the fuel mass in chute 2. The mixture of furnace gases and distillation gases withdrawn from feed chute 2 90 passes through the passage 15, blower 16 and passage 17, as already stated, into the lower part of cooler 3. Passing up through cooler 3 this cold gas is brought into contact with the hot material which has passed over the 95 grate, and which is, of course, initially at a high temperature on its entrance into 3, and takes up the heat from this discharged fuel and is itself heated nearly to the temperature at which the fuel passes through the 100 space 18. If the gases passing up through cooler 3 contain any considerable amount of gases which react with incandescent carbon (e. g. carbon dioxid, water vapor or hydro-carbon gases) more or less of such gases will 105 undergo reduction in contact with the incandescent carbonized fuel in the upper part of 3, generating combustible gas.

When my invention is being used for the so-called direct firing of a boiler or other heating apparatus the gases discharging from the fuel mass on grate 4 will contain more or less free oxygen. This is due to the fact that in order to secure a sufficiently rapid combustion of the solid fuel on 4 it is necessary to supply to the fuel an amount of air in excess of that carrying the quantity of oxygen with which the fuel can react. In other words, it is necessary to maintain a considerable proportion of free oxygen in 110 the atmosphere in contact with the fuel in order to secure a reasonably rapid combustion. To insure such an excess of oxygen it is therefore necessary to add to the combustion gases proper a greater or less volume of gases which do not contribute to the heat generated in the combustion of the fuel on grate 4. This of course would reduce the 115 initial temperature of the gases going to the boiler or other heating apparatus since there 120

125
130

would be a greater volume of gas to be heated by the combustion. By my invention I correct this necessary result of the so-called direct firing by the combustion which takes place between the combustible containing gas ascending from the cooler 3 and the excess oxygen mentioned. The combustible constituents in the gases from the cooler 3 are burned, either wholly or in part, according to the proportion of free oxygen present. Indeed, in this embodiment of my invention, it is advantageous to supply to the fuel on grate 4 a sufficient volume of air to insure the presence in the gases discharging from the fuel on the grate 4, of a sufficient proportion of free oxygen to burn the combustible constituents of the gases passing into furnace chamber 1 from the cooler 3. By this feature of my invention and the proper regulation of the rate of advance of the fuel over grate 4, therefore, I am able to burn the solid fuel on the grate 4 under conditions which are favorable to a very rapid combustion of the fuel, since I am able to pass through the fuel mass a relatively large volume of air so well distributed that practically every particle of the fuel is surrounded with an atmosphere containing free oxygen without the necessity of having any considerable quantity of free oxygen in the hot combustion gases passing to the heat utilizing apparatus. The combustion gases discharging from the chamber 11 can thus be maintained at the highest practicable temperature. Since the speed of heating (in a boiler, for example) depends largely upon the temperature difference maintained between the heating gases and the heat receiving material the utility and importance of this result of my invention is obvious.

When using the second embodiment of my invention in which the fuel is burned in a thick bed to form principally carbon monoxid, the gas drawn up through the fuel in the feed chute 2 is, of course, what is technically known as "producer gas". To this is added the distillation gases derived from the volatile matter of the fuel. When this gas mixture is passed up through the fuel in the cooler 3, there will be but little reaction with the fuel in this case, but the sensible heat of the fuel in excess of the temperature at which the gas is introduced into cooler 3 will be taken up by the gas current and the gases will enter the space 11 and mingle with the main stream of gas generated in 1. This modification of my invention I do not claim specifically herein, it forming the matter claimed in my divisional application Ser. No. 660449, filed Nov. 15th, 1911. This method of making combustible gas is only claimed herein in its generic relation to the broad invention.

During ordinary operation I aim to draw off through 15 and introduce into the cooler

3 in the manner described a sufficient volume of cold gas to cool the fuel discharged from the combustion chamber down to approximately the temperature of the gas introduced by the time the fuel and ash mixture 70 has reached the discharging apparatus 5. By this device I am able to withdraw from the combustion chamber a sufficient proportion of coked coal to largely prevent clinkering even when using highly caking coals 75 without incurring any loss of heat by so doing. Owing to this fact, I am able to force through the furnace a much greater volume of draft than is possible in ordinary firing and so can work with a much thicker 80 bed of fuel on the grate 4 and still obtain a completely burned effluent gas. As is well known, in ordinary boiler firing it is not possible to maintain a thickness of more than about 6 inches of fuel and ash on the grates 85 without seriously retarding the passage of the draft. This is due to the action of the coal under high temperatures mentioned whereby it assumes a soft pasty condition which tends to form the fuel into aggregates or "cake", thereby closing up the interstices of the fuel and making the passage of the draft difficult. I am thus able to secure a much greater rate of combustion of the fuel per square foot of grate surface (or 95 per square foot of cross-section of the fuel bed) than is possible either in direct-fired furnaces or producers operated in the ordinary manner.

When the furnace is operated with the 100 grate shown in the position of Fig. 2 there is no material difference from the method of operation already described, except that the form of combustion in the furnace 1 is now changed to the imperfect combustion of carbon to carbon monoxid, such as occurs in the ordinary gas producer. In this case the gas discharging through the flue 12 has, of course, more or less of the character of producer gas and now requires an additional 105 supply of air in order to effect complete combustion. In this case the gas can be conducted to a furnace situated at a distance and there burned the same as ordinary 110 producer gas.

From the above description it is obvious that with my method of conducting combustion the stoking of the fuel bed is entirely automatic, the movement of the fuel through the furnace being accomplished entirely by 120 gravity and not requiring any mechanical power-operated stoking device. The advantage of this will be very apparent to those skilled in the art, since it is well known that mechanical stokers are subject to great wear 125 and are very liable to get out of order. Besides this, the initial cost is high, and I can erect a furnace to operate under my system at a much less outlay than is required to install a mechanically stoked plant. 130

As before stated, my invention may be used with either intermittent or continuous operation without affecting the principles of operation on which my invention is based.

5 It is to be noted that in diverting a portion of the combustion gases from chamber 1 through the fuel chute 2 I do not thereby sacrifice any of the heat generated in the combustion chamber 1, since in passing 10 through the cold fuel practically all the sensible heat which the gases initially hold is given up to the fresh fuel which is passed to the grate. Indeed, this preheating of the fuel is a very decided advantage since it 15 enables me to bring the fuel onto the grate 4 at a temperature approximating that which is normally established in the fuel on 4 by the combustion. There is thus no momentary chilling of the furnace such as occurs 20 when charging the ordinary direct fired boiler furnace.

By my invention I am able to secure much more uniform firing of a boiler or other apparatus than is at all possible by 25 means of the ordinary direct fired furnace. Besides this, the free passage which is always open to the draft current through the fuel bed on grate 4 or in chamber 1 makes it possible to maintain a practically constant 30 draft through the furnace and heat utilizing chamber which is not possible in the ordinary manner of firing. In ordinary firing the fuel bed is constantly varying in regard to the proportion of interstices which it 35 contains and for this reason the back pressure on the draft current is constantly varied. In order to maintain a constant volume of draft, therefore, in this case it is necessary to be constantly varying the 40 discharge of steam through the blower 9, or the speed of the mechanical blower when such is substituted for 9, in order to force a constant volume of air through the grate. Since such constant attention to the draft 45 is impracticable in ordinary firing, the result is that the volume of draft is constantly varied. This, in turn, produces a constantly varying steam generating effect in the boiler itself. In plants where the rate of steam 50 generation is designed to closely approximate the rate of steam consumption, in order to maintain a uniform pressure for the engine it is absolutely necessary to provide steam drums of large capacity so that the 55 fluctuation in steam generation may be, so to speak, governed by having a large reservoir of steam upon which the engines may draw during periods of low steam generation. By my method of operation, on the 60 contrary, it is possible, where the load is practically uniform, to operate with very small steam drums. The advantage of this regular and uniform firing which I am able to secure by applying my method of 65 operation to furnaces is of equal advantage

when the apparatus heated is an ordinary furnace as when it is used for heating a boiler. Indeed, in many metallurgical operations the maintenance of uniform firing is of more importance than in boiler operation. My invention, therefore, is peculiarly well adapted for firing such furnaces.

70 While I have described above the method of operation which I deem the most advantageous, it is to be understood that modifications may be made in the details of operation without departing from my essential process. For example, instead of using cold combustion gas alone to cool the fuel and ash in the cooler 3, I may use a mixture of 75 80 combustion gas and steam, or steam alone. Or I may, instead of using the hot gases from the furnace itself to preheat the cold fuel, use hot waste combustion gases from a metallurgical furnace where such are 85 available. If the preheating of the fuel is not deemed necessary, this operation may 90 also be dispensed with.

The main and indispensable features of 95 my invention I consider to be the passing of the fuel through the combustion chamber at a rate greater than that of combustion in the chamber, the cooling of the material discharged from the chamber and the return 95 to the combustion chamber in admixture with fresh fuel.

The application of this invention to the 100 operation of a gas producer I do not specifically claim herein, this forming the matter of another application.

The method of heat recuperation by restoring the heat of material advancing beyond a zone of combustion to the material in the combustion zone and to the material 105 advancing to said zone by utilizing a gaseous current as the medium of transfer, I do not claim broadly herein, that forming part of the matter of my prior and co-pending application Ser. No. 535,841, filed Dec. 110 31st, 1909. Nor do I claim broadly herein this method of heat recuperation as applied to the coking and distillation of coal where such combustion is a mere incident to said coking and where distillation gases are recovered for use elsewhere, this being part 115 of the matter of co-pending applications.

Having described my invention, what I claim is:

1. The method of conducting combustion 120 which comprises, advancing a column of fuel through a relatively long conduit having an intermediate localized combustion zone, withdrawing from said combustion zone a portion of the combustion gases formed 125 therein, passing the said portion of combustion gases in contact with the portion of said fuel column advancing toward said combustion zone to preheat the fuel in said portion of said column and to cool said 130

- gases, conducting the cooled and non-combustion-supporting gases to the portion of said fuel column advancing through said conduit beyond said combustion zone, and contacting 5 said cooled gases with the material in the said column beyond said combustion zone, to cool the said material and to heat said gases.
2. The method of conducting combustion which comprises, advancing a column of 10 fuel through a relatively long conduit having an intermediate localized combustion zone, withdrawing from said combustion zone a portion of the combustion gases formed therein, said combustion gases being of non-combustion-supporting character, passing the said portion of combustion gases in contact with the portion of said fuel column advancing toward said combustion zone to preheat the fuel in said 15 portion of said column and to cool said gases, conducting the cooled non-combustion-supporting gases to the portion of said fuel column advancing through said conduit beyond said combustion zone, and contacting 20 said cooled non-combustion-supporting gases with the material in the said column beyond said combustion zone, the volume of said portion of cooled combustion gases being that which will suffice to cool the 25 material in the portion of the said fuel column beyond said combustion zone to the desired degree.
3. The method of conducting combustion which comprises, advancing a column of 30 fuel through a relatively long conduit having an intermediate combustion zone, at a rate greater than the rate of combustion of said fuel in said zone, and quenching unconsumed material in that portion of said 35 column beyond said combustion zone by contacting with said material a stream of a relatively cool gas containing less free oxygen than that required to maintain the combustion of the combustible matter in said 40 material, to cool said material and to heat the said gas stream, and passing the so-heated gas in contact with the fuel in that portion of said fuel column in said combustion zone.
4. The method of conducting combustion which comprises, feeding fuel through a combustion zone at a rate greater than the rate of combustion of said fuel therein, the 45 rate of feed of said fuel being that required to insure a sufficient proportion of unburned fuel in the mixture of fuel and ash discharged from said combustion zone to maintain said mixture in a condition easily permeable by the draft current, removing unburned fuel and ash from said zone, and returning to the said combustion zone heat carried out of said zone by the unburned fuel and by the ash of said burned fuel, by 50 conducting cool non-combustion-supporting 55 gas through said mixture and into said combustion zone.
5. The method of conducting combustion which comprises, feeding fuel through a combustion zone by gravity at a rate greater than the rate of combustion of said fuel therein, the rate of feed of said fuel being that required to insure a sufficient proportion of unburned fuel in the mixture of fuel and ash discharged from said combustion zone to maintain said mixture in a condition easily permeable by the draft current, removing unburned fuel and ash from said zone, and returning to the said combustion zone heat carried out of said zone by the unburned fuel and by the ash of the burned fuel, by 60 conducting cool non-combustion-supporting gas through said mixture and into said combustion zone.
6. The method of conducting combustion which comprises, feeding fuel through a combustion zone at a rate greater than the rate of combustion of said fuel therein, the rate of feed of said fuel being that required to insure a sufficient proportion of unburned fuel in the mixture of fuel and ash discharged from said combustion zone to maintain said mixture in a condition easily permeable by the draft current, removing unburned fuel and ash from said zone, and returning to the said combustion zone heat carried out of said zone by the unburned fuel and by the ash of the burned fuel by first contacting a non-combustion supporting gas with the unburned fuel and ash and then introducing the said gas into the fuel 85 in said zone.
7. The method of conducting combustion which comprises feeding fuel through a combustion zone at a rate greater than the rate of combustion of said fuel therein, the rate of feed of said fuel being that required to insure a sufficient proportion of unburned fuel in the mixture of fuel and ash discharged from said combustion zone to maintain said mixture in a condition easily permeable by the draft current, removing unburned fuel and ash from said zone, contacting with the unburned fuel and the ash of the burned fuel a stream of an initially cool non-combustion-supporting gas 90 to cool said unburned fuel and ash and to heat the said gas, and conducting the said heated non-combustion-supporting gas into the said combustion zone.
8. The method of conducting combustion which comprises, feeding fuel through a combustion zone at a rate greater than the rate of combustion of said fuel therein, the rate of feed of said fuel being that required to insure a sufficient proportion of unburned fuel in the mixture of fuel and ash discharged from said combustion zone to maintain said mixture in a condition eas- 95 100 105 110 115 120 125

ily permeable by the draft current, removing unburned fuel and ash from said zone, contacting with the unburned fuel and the ash of the burned fuel a stream of an initially cool non-combustion-supporting gas to cool said materials and to heat said gas, conducting the said heated gas into the said combustion zone and mingling the said heated gas with the draft current passing through said combustion zone, whereby heat carried out of said combustion zone by the said materials is returned to said zone.

9. The method of conducting combustion which comprises, feeding fuel through a combustion zone by gravity at a rate greater than the rate of combustion of said fuel therein, the rate of feed of said fuel being that required to insure a sufficient proportion of unburned fuel in the mixture of fuel and ash discharged from said combustion zone to maintain said mixture in a condition easily permeable by the draft current, removing unburned fuel and ash from said zone, and returning to the said combustion zone the major part of the heat carried out of said zone by the unburned fuel and by the ash of the burned fuel by contacting with the hot unburned fuel and ash a relatively cool non-combustion-supporting gas to heat said gas and passing the so-heated gas into said combustion zone.

10. The method of conducting combustion which comprises, feeding fuel by gravity through a combustion zone at a rate greater than the rate of combustion of said fuel therein, the rate of feed of said fuel being that required to insure a sufficient proportion of unburned fuel in the mixture of fuel and ash discharged from said combustion zone to maintain said mixture in a condition easily permeable by the draft current, removing unburned fuel and ash from said zone, contacting with the said unburned fuel and ash of the burned fuel a stream of an initially cool non-combustion-supporting gas to cool the said materials and to heat the said gas, conducting the said heated gas into the said combustion zone and mingling the said heated gas with the draft current passing through said combustion zone, whereby heat carried out of said combustion zone by the said materials is returned to said zone.

11. The method of conducting combustion which comprises, feeding fuel through a combustion zone at a rate greater than the rate of combustion of said fuel therein, the rate of feed of said fuel being that required to insure a sufficient proportion of unburned fuel in the mixture of fuel and ash discharged from said combustion zone to maintain said mixture in a condition easily permeable by the draft current, removing unburned fuel and ash from said zone, re-

turning to the said combustion zone heat carried out of said zone by the unburned fuel and the ash of the burned fuel, separating the said unburned fuel from said ash, and returning the said unburned fuel to said combustion zone in admixture with fresh fuel.

12. The method of conducting combustion which comprises, feeding fuel to and through a combustion zone at a rate greater than the rate of combustion of said fuel therein, the rate of feed of said fuel being that required to insure a sufficient proportion of unburned fuel in the mixture of fuel and ash discharged from said combustion zone to maintain said mixture in a condition easily permeable by the draft current, removing unburned fuel and ash from said zone, contacting with the said unburned fuel and ash of the burned fuel a stream of an initially cool gaseous fluid to cool the said unburned fuel and ash of the burned fuel and to heat said gaseous fluid, separating the said unburned fuel from said ash and returning unburned fuel to said combustion zone in admixture with fresh fuel.

13. The method of conducting combustion which comprises, feeding fuel through a combustion zone at a rate greater than the rate of combustion of said fuel therein, the rate of feed of said fuel being that required to insure a sufficient proportion of unburned fuel in the mixture of fuel and ash discharged from said combustion zone to maintain said mixture in a condition easily permeable by the draft current, removing unburned fuel and ash from said zone, contacting with the unburned fuel and the ash of the burned fuel a stream of an initially cool gaseous fluid to cool the said materials and to heat the said gaseous fluid, conducting the heated fluid into the said combustion zone, mingling the said heated fluid with the draft current passing through said combustion zone, whereby the heat carried out of said combustion zone by the said materials is returned to said zone, separating the said unburned material from said ash and returning separated unburned material to said combustion zone in admixture with fresh fuel.

14. The method of conducting combustion which comprises, feeding fuel by gravity through a combustion zone at a rate greater than the rate of combustion of said fuel therein, the rate of feed of said fuel being that required to insure a sufficient proportion of unburned fuel in the mixture of fuel and ash discharged from said combustion zone to maintain said mixture in a condition easily permeable by the draft current, removing unburned fuel and ash from said zone, contacting with the said unburned fuel and ash of the burned fuel a stream of an initially

cool gaseous fluid to cool the said materials and to heat the said gaseous fluid, conducting the said heated fluid into said combustion zone, separating the said unburned fuel 5 from the said ash and returning the said unburned fuel to said combustion zone in admixture with fresh fuel.

15. The method of conducting combustion which comprises, feeding fuel by gravity 10 through a combustion zone at a rate greater than the rate of combustion of said fuel therein, removing unburned fuel and ash therefrom, contacting with the unburned fuel and the ash of the burned fuel a stream 15 of an initially cool gaseous fluid to cool the said materials and to heat the said gaseous fluid, conducting the heated fluid into the combustion zone and mingling the said heated fluid with the draft current passing 20 through said combustion zone, whereby heat carried out of said combustion zone by the said materials is returned to said zone, separating the said unburned materials from said ash and returning the said unburned 25 material to said combustion zone in admixture with fresh fuel, the proportion of the returned fuel in the mixture being that required to substantially prevent the caking of the said fresh fuel.

30. 16. The method of conducting combustion which comprises, feeding a mixture of fresh and carbonized fuel in regulated proportions to a combustion zone at a rate greater than the rate of combustion of said fuel therein, 35 the rate of feed of said fuel being that required to insure a sufficient proportion of unburned fuel in the mixture of fuel and ash discharged from said combustion zone to maintain said mixture in a condition easily 40 permeable by the draft current, burning a portion of said fuel in said combustion zone, removing unburned fuel and ash therefrom, separating unburned fuel from ash of the burned fuel, returning the said unburned 45 fuel to the said combustion zone in admixture with fresh fuel, withdrawing from said combustion zone a portion of the gases generated in said zone and passing said portion of gases in contact with the said mixture of 50 carbonized and fresh fuel being fed to said zone to heat the said fuel mixture prior to introducing the same into said zone to cool the said portion of said gases.

17. The method of conducting combustion 55 which comprises, feeding a mixture of fresh and carbonized fuel by gravity to a combustion zone at a rate greater than the rate of combustion of said fuel therein, the rate of feed of said fuel being that required 60 to insure a sufficient proportion of unburned fuel in the mixture of fuel and ash discharged from said combustion zone to maintain said mixture in a condition easily permeable by the draft current, removing unburned 65 fuel and free ash from said zone,

separating unburned fuel from ash of the burned fuel, returning the separated unburned but carbonized fuel to the said combustion zone in admixture with fresh fuel, withdrawing from said zone a portion of the 70 gases generated in said zone and passing said portion of said gases in contact with the said mixture of carbonized and fresh fuel which is being fed to said zone to preheat the said fuel mixture prior to introducing the same into said zone and to cool the said portion of gases.

18. The method of conducting combustion which comprises, feeding a mixture of fresh and carbonized fuel by gravity to a combustion zone at a rate greater than the rate of combustion of said fuel therein, burning a portion of said fuel in said zone, withdrawing unburned but carbonized fuel and free ash therefrom, separating unburned fuel 80 from ash of the burned fuel, returning separated unburned fuel to said combustion zone in admixture with fresh fuel, the proportion of unburned fuel in said mixture being that required to maintain the fuel bed in said 85 combustion zone in a condition permeable by the draft current passing therethrough, and preheating the said fuel mixture prior to introducing the same into said combustion zone by passing in contact therewith a 90 stream of initially hot gases.

19. The method of conducting combustion which comprises, preheating a body of fuel by contacting therewith a current of hot gases, feeding the preheated fuel through a 100 combustion zone at a rate greater than the rate of combustion of said fuel therein, the rate of feed of said fuel being that required to insure a sufficient proportion of unburned fuel in the mixture of fuel and ash discharged from said combustion zone to maintain said mixture in a condition easily permeable by the draft current, burning a portion of said fuel in said combustion zone, removing unburned but carbonized fuel and free ash therefrom, contacting with the said unburned but carbonized fuel and free ash a stream of an initially cool gaseous fluid to cool the said materials and to heat the said 110 gaseous fluid, conducting the said heated fluid into the said combustion zone and mingling the said heated fluid with the draft current passing through said combustion zone, whereby heat carried out of said zone by the said materials is returned to said zone.

20. The method of conducting combustion which comprises, feeding fuel through a combustion zone at a rate greater than the rate of combustion of said fuel in said zone, burning a portion of said fuel in said zone, removing unburnt but carbonized fuel and free ash from said zone, returning to the said zone heat carried out of said zone by the unburned fuel and by the ash of the burned fuel by contacting therewith a 115 120 125 130

stream of initially cool gaseous fluid to cool said fuel and ash and to heat said fluid and separating the sedimented fluid to the said combustion zone, separating the cooled unburned but carbonized fuel from unburned ash, mixing the said unburned fuel with a portion of fresh fuel, preheating the resulting mixture by contacting therewith a stream of initially hot gases, and feeding the preheated mixture to said combustion zone.

21. The method of conducting combustion which comprises, feeding fuel through a combustion zone at a rate greater than the rate of combustion of said fuel, burning a portion of said fuel in said zone, removing unburned but carbonized fuel and ash from said zone, contacting with the unburned carbonized fuel and the ash of the burned fuel a stream of an initially cool gaseous fluid to cool said materials and to heat the said fluid, conducting the heated fluid into said combustion zone and mixing the said fluid with the draft current passing through said zone, whereby heat carried out of said zone by the said materials is returned to said zone, separating unburned carbonized fuel from said ash, mixing a regulated quantity of fresh fuel with said unburned carbonized fuel, preheating the fuel mixture by contacting therewith a current of hot gases and feeding the preheated fuel mixture into said combustion zone.

22. The method of conducting combustion which comprises, feeding fuel through a combustion zone by gravity at a rate greater than the rate of combustion of the fuel thereon, burning a portion of said fuel in said zone, separating unburned but carbonized fuel and ash from said zone, separating unburned carbonized fuel from free ash, burning a quantity of fresh fuel with the separated unburned carbonized fuel, the proportion of said carbonized fuel in the resulting mixture being that which will maintain the fuel bed in said zone in a condition permitting a free passage of the draft current therethrough, preheating the said fuel mixture by contacting therewith a stream of initially hot gases, and feeding the preheated mixture into said combustion zone.

23. The method of conducting combustion which comprises, feeding a mixture of fresh and carbonized fuel in regulated proportions to a combustion conduit at a rate greater than the rate of combustion of said fuel thereon, burning a portion of said fuel in a combustion zone located at an intermediate section of said conduit, withdrawing unburned but carbonized fuel and free ash from said combustion zone and advanc-

ing them into a fuel-cooling zone, withdrawing the minor portion of the hot combustion gases formed in said combustion zone from said zone and passing the said gases in contact with another volume of the mixture of fresh and carbonized fuel intended for said zone to prevent the said mixture and to cool the said gases, conducting the cooled gases to said fuel-cooling zone and there contacting them with the hot mixture of unburned but carbonized fuel and ash discharged from the said combustion zone to cool the said mixture.

24. The method of conducting combustion which comprises, feeding a mixture of fresh and carbonized fuel to a comparatively long fuel conduit, advancing said fuel mixture into a combustion zone at a rate greater than the rate of combustion of said fuel in said zone, burning a portion of the fuel mixture in said combustion zone, withdrawing the resulting mixture of unburnt carbonized fuel and free ash from said combustion zone into a fuel-cooling zone, withdrawing a minor portion of the hot combustion gases formed in said combustion zone from the said zone and passing the said portion of combustion gases in contact with another volume of the mixture of fresh and carbonized fuel intended to be burned in said zone to prevent the said mixture and to cool the said gases, conducting the cooled gases to said fuel-cooling zone and there contacting the said cooled gases with the hot mixture of unburned carbonized fuel and the ash residue withdrawn from the said combustion zone to cool said fuel mixture of unburned carbonized fuel and ash with a quantity of fresh fuel to form another volume of fuel mixture of regulated composition for said combustion zone.

25. The method of conducting combustion which comprises, feeding by gravity a mixture of fresh and carbonized fuel in regulated proportions to a fuel conduit, advancing the said mixture to a combustion zone at a rate greater than the rate of combustion of said fuel in said zone, burning a portion of said fuel in said zone, withdrawing unburned carbonized fuel and free ash from said combustion zone to a fuel-cooling zone, withdrawing a minor portion of the hot combustion gases produced by the burning of said portion of fuel from said combustion zone and passing the same in contact with another volume of the mixture of fresh and carbonized fuel intended to be burned in said zone to preheat the said mixture and to cool the said portion of gases, conducting the cooled gases to said fuel-cool-

- ing zone and there contacting the said cooled gases with the hot mixture of unburned carbonized fuel and the ash withdrawn from the said combustion zone to cool the said mixture of fuel and ash, conducting a major portion of the said combustion gases to a heat utilizing apparatus, withdrawing the cooled mixture of fuel and ash from said fuel-cooling zone, separating the unburned 5 carbonized fuel from the said ash and mixing the separated carbonized fuel in regulated proportion with a quantity of fresh fuel to form another volume of fuel mixture, the proportion of coked fuel in said 10 mixture being that which will prevent the caking of the said fresh fuel.
26. The method of conducting combustion which comprises, feeding a mixture of fresh fuel and carbonized fuel of regulated 20 composition to a fuel conduit, advancing the said fuel mixture into a combustion zone at a rate greater than the rate of combustion of said fuel therein, burning a portion of said fuel in said combustion zone, 25 discharging the unburned but carbonized fuel and free ash from the burned fuel from said combustion zone, withdrawing a minor portion of the hot gases formed by said combustion from said zone and passing the said 30 minor portion in contact with a volume of the mixture of fresh and carbonized fuel in said fuel conduit to preheat the said mixture and to cool the said gases, conducting the cooled gases to and passing them in 35 contact with the mixture of carbonized fuel and ash discharged from the said combustion zone, the volume of the gases so withdrawn from said combustion zone and contacted with the fuel in said fuel conduit in 40 a given interval of time being regulated to the volume required to cool the quantity of ash and carbonized fuel discharged from the said combustion zone in a corresponding period of time.
45. 27. The method of conducting combustion which comprises, feeding by gravity to a fuel conduit a mixture of fresh fuel and carbonized fuel in regulated proportions, advancing the said mixture to a combustion 50 zone at a rate greater than the rate of combustion of said fuel in said zone, burning a portion of said fuel in said zone, discharging the unburned but carbonized fuel and the ash residue from the burned fuel from 55 said zone, withdrawing a minor portion of the hot combustion gases formed by the said combustion from said zone, passing the said minor portion of combustion gases in contact with another volume of the said mixture of fresh and carbonized fuel in said fuel conduit to preheat the said mixture and to cool the said portion of gases, conducting the cooled gases to and passing them in 60 contact with the mixture of carbonized fuel and ash discharged from the said combustion 65 zone, separating the carbonized fuel from the said ash and mixing a regulated quantity of fresh fuel with the said carbonized fuel to form another volume of the fuel mixture for said combustion zone, the proportion of the carbonized fuel in the said mixture being that required to maintain the fuel bed in said combustion zone in a condition permitting the easy passage of the draft current therethrough.

28. The method of conducting combustion which comprises, feeding a mixture of fresh fuel and carbonized fuel in regulated proportions to a fuel conduit, advancing said fuel mixture into a combustion zone at a rate greater than the rate of combustion of said fuel therein, burning a portion of said fuel in said zone, discharging the unburned but carbonized fuel and the ash from the burned fuel from said combustion zone, withdrawing a minor portion of the hot combustion gases formed by said combustion from said zone and passing the said gases in contact with a volume of the mixture of fresh and carbonized fuel in said fuel conduit to preheat the said mixture and to cool the said gases, conducting the cooled gases to and passing them in contact with the said mixture of carbonized fuel and free ash discharged from said combustion zone, the volume of the said portion of gases withdrawn from the said combustion zone and contacted with the fuel mixture in said conduit in a given interval of time being regulated to substantially the volume required to cool the quantity of ash and carbonized fuel discharged from the said zone in the same period of time, separating the carbonized fuel from the said ash and mixing a regulated quantity of fresh fuel with the said carbonized fuel to form another volume of the fuel mixture for said combustion zone, the proportion of the carbonized fuel in the said mixture being that required to maintain the fuel bed in said combustion zone in a condition permitting the easy passage of the draft current therethrough.

29. The method of conducting combustion which comprises, feeding by gravity a mixture of fresh fuel and carbonized fuel in regulated proportions to a fuel conduit, advancing the said mixture into a combustion zone at a rate greater than the rate of combustion of said fuel therein, burning a portion of said fuel in said zone, withdrawing the unburned but carbonized fuel and the ash from the burned fuel from said combustion zone and advancing them into a cooling zone at a rate such as will insure the presence of sufficient unburned but carbonized fuel in said mixture of fuel and ash in said cooling zone to render the said mixture easily permeable by the draft current, withdrawing a portion of the hot combustion gases formed in the combustion of said portion of the fuel from said zone and passing the said gases in contact with a volume of

- the mixture of fresh and carbonized fuel advancing toward said zone to preheat said mixture and to cool the said gases, conducting the cooled gases to and passing them in 5 contact with the said hot mixture of carbonized fuel and ash withdrawn from said combustion zone, the volume of the said portion of gases withdrawn from the said combustion zone in a given interval of time being 10 regulated to substantially the volume required to cool the quantity of ash and carbonized fuel discharged from the said zone in the same period of time to the desired degree, separating the carbonized fuel from 15 the said ash and mixing a regulated quantity of fresh fuel with the said carbonized fuel to form another volume of the fuel mixture for said combustion zone, the proportion of carbonized fuel in the said mixture being 20 that required to substantially prevent the obstruction of the draft through said combustion zone by the caking of the fresh fuel.
30. The method of conducting combustion which comprises, maintaining a body of fuel in a comparatively long conduit in such manner that the said body of fuel will be caused to move through a combustion zone of said conduit as the fuel mass is removed from the lower part of said conduit, 25 removing material from the extremity of said fuel body beyond said combustion zone and adding fresh fuel to the portion of said fuel body in advance of said combustion zone, maintaining combustion in the middle 30 portion of said fuel body, with the production of gases of complete combustion by supplying a regulated quantity of air to said middle portion only of said fuel body, the volume of air so supplied being so correlated to the rate of advance of said fuel body that a substantial proportion of said fuel will pass through the said combustion zone unburned to insure the presence of sufficient unburned fuel mixed with the ash in 35 the portion of said fuel body beyond said combustion zone, to keep the material in the said portion of said fuel body in a condition permitting easy penetration of said portion of said fuel body by a combustion- 40 quenching fluid, passing sufficient of said combustion-quenching fluid through the said portion of said fuel body to extinguish the said ignited unburned fuel therein, and withdrawing the material from the said portion of said fuel body in a quenched and 45 comparatively cool condition.
31. The method of conducting combustion which comprises, maintaining a body of fuel in a furnace zone in such manner that the 50 said body of fuel will be caused to move through said zone as the fuel mass is removed from the lower part of said zone, removing material from the bottom of said body of fuel and charging fresh fuel onto 55 the top of said body of fuel, maintaining combustion in the middle portion of said body of fuel by supplying air to said middle portion, the volume of air so supplied being such that a substantial proportion of the fuel entering said combustion zone will 60 pass through the same unconsumed, and contacting with the residual mixture of carbonized fuel and ash that has passed through the said middle portion of said body of fuel a stream of initially cool non-combustion supporting gas, the volume of the said gas relative to the speed of advance of the said residual mixture being that required to quench the unburned fuel in the said mixture and to cool the said residual mixture to the extent desired.
32. The method of conducting combustion which comprises, maintaining a body of fuel in a furnace zone in such manner that the said body of fuel will be free to move 65 through the said zone under the influence of gravity as the fuel mass is removed from the bottom of said zone, removing material from the bottom of said body of fuel and charging fresh fuel onto the top of said body of fuel, maintaining combustion in the middle portion of said body of fuel by supplying air to said middle portion, the volume of said air being so correlated to the rate of movement of said fuel body that sufficient unburned but carbonized fuel will remain in the material in the lower part of said fuel body to keep the said lower part in a condition permitting easy penetration of said lower part by the draft current, and 70 contacting with the residual mixture of carbonized fuel and ash that has passed through the said middle portion of said body of fuel a stream of initially cool non-combustion-supporting gas, the volume of the said gas relative to the volume of the said residual mixture being that required to cool the said residual mixture to the desired extent.
33. The method of conducting combustion 75 which comprises, advancing a body of fuel slowly through a combustion zone of a furnace chamber, the rate of advance of said body of fuel being regulated to that which will carry through the said combustion zone a sufficient quantity of unburned but carbonized fuel to maintain the said body of fuel easily permeable to the draft current supplied to said furnace and to establish a mixture of unburned fuel and 80 ash in said fuel body beyond said combustion zone, introducing a regulated volume of air into said combustion zone to maintain combustion therein, quenching the said mixture of unburned fuel and ash in the said portion of said fuel body beyond said combustion zone, withdrawing the said quenched mixture of unburned fuel and ash from said furnace, separating the relative coarse portion of 85 said mixture of quenched unburned fuel and 90

- ash comprising chiefly quenched unburned fuel from the relatively fine portion of the same comprising chiefly the ash of the burned fuel, mixing a regulated proportion 5 of fresh fuel with the separated unburned carbonized fuel and feeding the resulting mixture to the portion of said fuel body advancing toward the combustion zone of said furnace.
- 10 34. The method of conducting combustion which comprises, advancing a body of fuel slowly through a furnace chamber, the rate of said movement being that which will carry through a combustion zone of said 15 furnace chamber a sufficient quantity of unburned but carbonized fuel to maintain the body of fuel in said combustion zone in a condition affording a free passage to the draft current, introducing a regulated volume 20 of a combustion-supporting draft current into said combustion zone to maintain the combustion therein and conducting the gases of combustion to the place of use, cooling the mixture of carbonized fuel and ash 25 that has been carried through the combustion zone of said furnace chamber by contacting therewith a stream of relatively cool gaseous fluid, the volume of said gaseous fluid relative to the volume of the said mixture 30 of carbonized fuel and ash being that required to cool the said mixture to the degree desired, withdrawing the said fuel-ash mixture from said furnace chamber, separating the carbonized fuel of said mixture from 35 the ash of the same, mixing a regulated proportion of fresh fuel with the said carbonized fuel and feeding the resulting mixture onto the top of the body of fuel in said furnace.
- 40 35. The method of conducting combustion which comprises, advancing a body of fuel slowly through a furnace chamber, the rate of advance of said fuel relative to the volume of the draft current of said furnace 45 being that which will carry through a combustion zone of said furnace chamber a sufficient quantity of unburned but carbonized fuel to maintain the body of fuel in said combustion zone in a condition affording a free passage to the draft current, introducing a regulated volume of combustion-supporting draft current into said combustion zone to maintain the combustion therein, conducting the major part of the gases produced by said combustion to the place of use, conducting the minor part of the said gases in contact with the upper portion of the body fuel in the said furnace to preheat the same and to cool the said minor portion of the said gases, conducting the cooled gases to and contacting them with the mixture of carbonized fuel and ash that has been carried through the combustion zone of said furnace, the volume of the said minor stream being that required to cool the said mixture to the degree desired, conducting the said minor stream after the same has been contacted with the said mixture of carbonized fuel and ash back to the said combustion zone, withdrawing the cooled mixture of fuel and ash from the said furnace, mixing fresh fuel with the said carbonized fuel and feeding the said mixture onto the top of the body of fuel in said furnace chamber, the proportion of the carbonized fuel in the said fuel mixture being that which is required to reduce the caking and clinkering of the fuel bed to the desired degree.
- 50 36. The method of conducting combustion which comprises, maintaining a body of fuel in a furnace chamber in such manner that the said fuel will be free to move through the said chamber under the influence of gravity as the fuel mass is removed from the bottom of said furnace chamber, the said fuel mass at the same time maintaining in the combustion chamber of said furnace a free surface on its natural angle of repose, removing regulated portions of quenched unconsumed fuel and ash from the bottom of the body of fuel at a rate which 55

therein, conducting the major part of the gases produced by said combustion to the place of use, conducting the minor part of the said gases in contact with the upper portion of the body of fuel in the said furnace to preheat the same and to cool the said minor portion of the said gases, conducting the cooled gases to and contacting them with the mixture of carbonized fuel and ash from 5 the combustion zone of said furnace, the volume of the said minor stream being that required to cool the said mixture to the degree desired, conducting the said minor stream after the same has been contacted 10 with the said mixture of carbonized fuel and ash back to said combustion zone to rejoin the main draft current, withdrawing the cooled mixture of carbonized fuel and ash from the said furnace, mixing a regulated proportion of fresh fuel with the said 15 carbonized fuel and feeding the said mixture onto the top of the said body of fuel in said furnace chamber.

42. The method of conducting combustion which comprises, maintaining a body of fuel in a furnace chamber in such manner that the said fuel will be free to move through the said chamber under the influence of gravity as the fuel mass is removed 20 from the bottom of said furnace chamber, the said fuel mass at the same time maintaining in the combustion region of said furnace a free surface on its natural angle of repose, removing either continuously or intermittently regulated portions of material from the bottom of the said body of fuel at a rate which will impart sufficient movement to the said fuel body relative to the rate of combustion of said fuel in a combustion region of the said furnace to carry through the said combustion region a sufficient quantity of unburned but carbonized fuel to maintain the fuel body in said region in a condition 25 easily permeable to the draft current, introducing a regulated volume of combustion-supporting draft current into said combustion region to maintain the combustion therein, conducting the major part of the gases produced by said combustion to the place of use, conducting the minor part of the said gases in contact with the upper portion of the body of fuel in the said furnace to preheat the same and to cool the said minor portion of the said gases to the degree desired, conducting the cooled gases to and contacting them with the mixture of carbonized fuel and ash from the combustion region of said furnace, the volume of the said minor stream being that required to 30 cool the said mixture to the degree desired, conducting the said minor stream after the same has been contacted with the said mixture of carbonized fuel and ash back to said combustion region to rejoin the main draft current, withdrawing the cooled mixture of

fuel and ash from the said furnace, mixing a regulated proportion of fresh fuel with the said carbonized fuel and feeding the said mixture onto the upper part of the said body of fuel in said furnace chamber, the proportion of the carbonized fuel in the said fuel mixture being that which is required to reduce the caking and clinkering of the fresh fuel to the desired degree. 70

43. The method of conducting the combustion of fuel which comprises, feeding the said fuel in an inclined layer through a furnace chamber, the angle of inclination of said layer being approximately equal to or greater than the angle of repose of the said fuel, the material discharging from the said layer being permitted to bank up from the bottom of the said furnace until the material in said layer has assumed its natural angle of repose, maintaining a column of fuel whose base is supported by the upper portion of the said layer, imparting a regulated movement to the fuel over said layer by withdrawing regulated portions of the material therein from the bottom of the said furnace, the rate of such movement being so regulated that there will always be a sufficient proportion of carbonized fuel maintained in the fuel mass on the layer to prevent caking and clinkering to the desired degree, separating the carbonized fuel in the mixture of unburned carbonized fuel and ash withdrawn from said ash pit, mixing a sufficient proportion of fresh fuel with the said carbonized fuel to give the desired 100 proportions of each in the fuel mixture and charging the said mixture onto the top of the said fuel column. 95

44. The method of conducting the combustion of fuel which comprises, feeding the said fuel in a comparatively thin inclined layer through a furnace chamber, the angle of inclination of said layer being approximately equal to or greater than the angle of repose of the said fuel, the material discharging from said layer being permitted to bank up from the bottom of the ash pit of said furnace until the material on the said layer has assumed its natural angle of repose, maintaining a column of fuel whose base is supported by the upper portion of the said layer, imparting a regulated movement to the fuel over said layer by withdrawing regulated portions of the material therein from the bottom of said furnace chamber, the rate of such movement being so regulated that there will always be a sufficient proportion of carbonized fuel maintained on the said layer to prevent caking and clinkering to the desired degree, 110 cooling the mixture of unburned but carbonized fuel and ash discharged from the said layer by contacting therewith a stream of a relatively cool gaseous fluid, withdrawing the said mixture from the said furnace 115 120 125 130

chamber, separating the carbonized fuel from the ash of the mixture, mixing a sufficient proportion of fresh fuel with the said carbonized fuel to give the desired proportions of each in the fuel mixture and charging the said mixture onto the top of the said fuel column.

45. The method of conducting the combustion of fuel which comprises, feeding the 19 said fuel in a comparatively thin inclined layer through a furnace chamber, the angle of inclination of said layer being approximately equal to or greater than the angle of repose of the said fuel, the material 20 discharging from said layer being permitted to bank up from a chamber below said layer until the material on the said layer has assumed its natural angle of repose, maintaining a column of fuel whose base is supported 20 by the upper portion of the said layer, imparting a regulated movement to the fuel over said layer by withdrawing regulated portions of the material therein from the bottom of the said chamber below said layer, the rate of such movement being so regulated 26 that there will always be a sufficient proportion of unburned carbonized fuel maintained in the fuel mass on the grate to prevent caking and clinkering to the desired 30 degree, withdrawing from above the layer a minor portion of the combustion gases

generated by the combustion maintained in the fuel mass therein, passing the said portion of combustion gases in contact with the unignited fuel in said fuel column, whereby 25 the said fuel is preheated and the said portion of gases cooled, conducting the cooled gases to the said chamber below said layer, contacting the said cooled gases therein with the mixture of unburned carbonized fuel 30 and free ash discharged from said layer, the volume of the said cooled gases being regulated to that required to cool the said mixture of carbonized fuel and free ash to the desired degree, conducting the major 35 portion of the said combustion gases to the place of use, withdrawing the cooled mixture of carbonized fuel and ash from said chamber, separating the carbonized fuel in the said mixture from the ash of the same, mixing a sufficient proportion of fresh fuel with the said carbonized fuel to give the desired proportions of each in the fuel mixture and charging the said mixture onto the top of the said fuel column.
